OF GÖTTENBORG, SWEDEN.

SASH WINDOW AND BALANCE.

No. 891,853.

Specification of Letters Patent.

Patented June 30, 1908.

Application filed May 10, 1907. Serial No. 372,975.

To all whom it may concern:

Be it known that I, JOHN NERÉN, a subject of the King of Great Britain, and resident of Örebro, Sweden, have invented new and useful Improvements in Sash Windows and Balances Therefor, of which the following is a specification, reference being had to the drawings accompanying and forming a part hereof.

- 10 This invention relates to apparatus for balancing sashes in sash-windows and particularly to such balancing apparatus of the kind consisting of a coiled spring inclosed within a pivotally mounted casing connected by a rope, a rack, or other suitable connection, with the sash in such a manner as to coil or uncoil the spring according as the sash is moved in one or the other direction. For 15 adjusting the tension of the spring in such an apparatus, a key has been employed by which the spindle of the casing is turned in one or the other direction, a catch connected with the spindle being released, when the key is inserted, so as to permit the turning of the 20 spindle, whereas, when the key is withdrawn, the catch is again thrown into action. In apparatus hitherto devised the regulating means referred to has been situated entirely outside the casing so as to occupy a considerable space.

One object of this invention is to obviate this inconvenience by placing the whole regulating device within the spring casing.

In apparatus of this kind a balancing can 35 be said to be obtained if the springs are able to retain the sash in any position between the extreme lower position and the extreme upper one but, on account of the springs slackening as the sash is raised, the retaining 40 power of the springs grows less and less as the sash is raised so that the power is often insufficient when the sash is near its highest position. It is true that this can be regulated by tightening the springs harder but in 45 such case the springs will, on the other hand, offer too great a resistance when the sash approaches its lowermost position. A further object of this invention is to overcome this latter drawback.

50 To the former end, the invention consists, chiefly, in making the spindle, or a part thereof, tubular in shape, or providing therein a cavity adapted to receive the catch-operating spring. The catch or other means 55 employed in order to normally prevent the

spindle from turning may also be situated within the spring casing. In this case the whole pivoted part of the apparatus may, outwardly, have the form of a cylinder, or a cylindrical disk, of the least possible dimensions and, furthermore, be so arranged that the casing of the apparatus can fit tightly to the latter, at both sides thereof. The apparatus, as a whole, will thus take up only little room and can easily be entered into the narrowest window-frames. On account of the latter property the apparatus is especially preferable to those hitherto known which, on account of the large space required by the same, cannot be generally used. The latter 65 object is attained by producing between the movable sash and the stationary frame a friction adapted to aid the springs in retaining the sash in any position without the said friction forming any obstacle to the free 70 movement of the sash up or down and without any hindering overtension of the springs causing a heavy movement of the sash being required.

The sash is suspended in a known manner 80 in two coiled springs each placed at one edge of the sash, and the said friction is produced by simply making the one spring somewhat stronger than the other. In consequence hereof, the sash is exposed to a torque tending 85 to turn the sash in a somewhat oblique position in the frame so that two diagonally opposite corners of the sash are pressed somewhat against the frame, thus affording the friction contributing to the retaining of the 90 sash. The turning of the sash in a somewhat oblique position is made possible by the greater or less windage always existing between the sash and the frame. When the sash is to be moved, the friction can, if 95 necessary, be easily removed by slightly turning the sash toward the side where the weaker spring is attached. Nevertheless, it may sometimes happen that the friction thus produced is not sufficient for retaining, 100 in conjunction with the springs, the sash in its uppermost position, and the invention to this end comprises a further arrangement hereinafter described.

In the drawings, which illustrate, by way 105 of example, in what manner the invention may be carried into effect, Figure 1 shows the inward side of a sash-window of the kind to which the invention relates, one of the balances being shown uncovered. Fig. 2 110

shows, in full size, a balance viewed from the side, partly in section. Fig. 3 is a horizontal section on line A—B of Fig. 2. Fig. 4 is a horizontal section of a balance. Fig. 5 is a similar view of the balance showing the parts in other positions. Figs. 6 and 7 show details appertaining to the apparatus illustrated in Figs. 4 and 5. Fig. 8 shows a modified form of the apparatus. Fig. 9 shows the same apparatus with the parts in other positions. Fig. 10 is a detail view of the same apparatus showing a section on line G—H in Fig. 8. Fig. 11 shows the arrangement for suspending the sash in such a manner as to produce the necessary friction between the sash and the frame assisting in balancing the sash. Fig. 12 is a horizontal section on line C—D of Fig. 11. Fig. 13 shows, in full size, a balance and an arrangement assisting in retaining the sash in its uppermost position. Fig. 14 shows the lastmentioned arrangement viewed from the edge of the sash. Fig. 15 is a horizontal section on line E—F of Fig. 13.

Referring to the drawings, each sash 1 is retained by two balances entered into the frame 2 at each side of the sash. Each balance consists of a box 3, or the like, in which two opposite sides form bearings 4 for a spindle 4 having a casing 5 loosely mounted thereon. The spring 6 inclosed within the said casing is attached, at one end, to the casing and at the other end to the spindle 4. The casing 5 is outwardly formed as a drum or pulley having wound thereon a line 7 or other flexible connection attached to and carrying the sash 1. Each sash is thus carried by two lines 7 each placed at one side of the sash as clearly seen in Fig. 11.

This balance works in such a manner that the weight of the sash is counterbalanced by the tension of the spring. By making the spring thin and of a suitable length, the tension imparted thereto can be kept nearly constant, so that the sash can be retained in any desired position of rest. Nevertheless, after some use the spring slackens and necessitates an adjustment. This adjustment is performed by means of the arrangement to be described.

In the embodiment illustrated in Figs. 4 to 7 the spindle 4 has, at its one end, a slot or groove 8 adapted to receive a catch 9, or the like. The catch 9 has two clutches 10 fitting in corresponding apertures 11 in the side-wall of the box 3. The clutches 10 are kept in engagement with the apertures 11 by a spiral spring 13 located in a bore in the spindle 4, by which the latter is secured in position.

In order to turn the spindle and, thereby, regulate the tension of the spring 6, a key 14 (Fig. 3) one end of which forms a blunt doghook, is inserted through a hole 12 in the frame 2. This hole is situated in the pro-

longation of the spindle 4, so that the end of the key 14 enters into the slot or groove 8 in the spindle 4. When pressure is exerted upon the key 14, the catch 9 is released and the spindle becomes free, whereupon the tension of the spring 6 can be increased or decreased at will by simply turning the key in one or the other direction. When the key is withdrawn, the spring 13 presses the clutches 10 into the apertures 11, so that the spindle is again secured in position.

In order to avoid the loose catch the somewhat modified arrangement illustrated in Figs. 8 to 10 can be employed. In this case the spindle 4 is made longitudinally movable and is provided with two diametrically opposite lugs 15. For turning the spindle a key similar to that described is employed, the spindle being moved lengthwise and the lugs 15 being disengaged by pressure upon the key inserted through the hole in the frame. When the key is withdrawn, the spindle is again locked in position by the spiral spring 13 pressing the lugs 15 into corresponding depressions 16 in the wall of the box 3.

The friction between the frame and the sash assisting in retaining the latter is obtained by the following arrangement. As before stated and clearly shown in Fig. 11, each sash is carried by two springs 6, each situated in a casing 5. Of these two springs, the one is stronger than the other, in consequence whereof the sash 1 is caused to take up an oblique position in the frame 2, as shown in Fig. 11, so that the diagonally opposite corners 17 and 18 of the sash 1 are somewhat pressed against the inside of the frame 2 and, thereby, produce the desired friction, by which the sash, with a comparatively slight coöperation of the spring power, so to say, carries itself.

The arrangement co-acting in retaining the sash in its uppermost position may consist of one or more curved springs 19 situated at one or both sides of the sash (see Figs. 13 and 14). One end of this spring is attached to the sash 1, while the other end is free to glide thereon by the same being provided with a longitudinal slot 20 (Fig. 14) adapted to receive a screw 21, or the like, by which the spring 19 is kept in contact with the sash. As easily understood, the spring will be straightened, if exposed to pressure from without, and then retain its curved form, when the pressure ceases. As shown in the drawings, the pulleys 5 project somewhat inside the frame 2, so that the lines 7 get totally clear and can be wound up between the edge flanges of the pulleys (see Figs. 13 and 15). These projecting parts of the pulleys will coöperate with the springs 19 in such a manner that, when the sash is raised and the springs 19 pass the pulleys 5, the latter straighten the said springs by pressing

same toward the sash so as to allow the latter to pass, whereupon the springs 19 retain their former shape and are supported by the pulleys 5, as shown in Fig. 13. The 5 springs 19 will then carry a great part of the weight of the sash. When the sash is lowered, the springs are first pressed toward the sash, when passing the pulleys. In lieu of the springs 19 elastic hooks or the like may 10 be employed and in lieu of the pulleys 5 other projecting parts adapted to carry the springs or similar elastic parts may be used. The springs or elastic parts can also be arranged at the inside of the frame 2 and the 15 projections coöoperating with the same be arranged at the sash.

Having now described my invention, what I claim as new and desire to secure by Letters Patent is:—

20 1. In a sash balance, the combination of a spindle, a coiled sash-balancing spring attached to the said spindle, a catch preventing the spindle from turning, when the sash-balancing spring is coiled or uncoiled, and a spring situated in a cavity in the spindle and acting to retain the catch in operative position, said catch being releasable by outward pressure against the action of the catch-retaining spring for enabling the tension of the 25 sash-balancing spring to be adjusted, substantially as and for the purpose set forth.

2. In a sash balance, the combination of a spindle, a coiled sash-balancing spring attached to the said spindle, a catch movably 35 mounted in a slot in the said spindle, and a spiral spring situated in a cavity in the spindle and acting to press the said catch in engagement with a stationary part, substantially as and for the purpose set forth.

40 3. In a sash-window, the combination of spindles journaled at each side of the sash, sash-balancing springs attached to the said spindles, one of the said springs being stronger than the other, means adapted to 45 prevent the spindles from turning, and springs situated in cavities in the spindles and acting to normally keep the said means operative, said means being releasable by outward pressure, substantially as and for 50 the purpose set forth.

4. In a sash-window, the combination of spindles journaled at each side of the sash, sash-balancing springs attached to the said spindles, one of the said springs being stronger than the other, means adapted to 55 prevent the spindles from turning, springs situated in cavities in the spindles and acting to normally keep the said means operative, said means being releasable by outward pressure, and elastically yielding parts carried by the sash, at the sides thereof, said parts being adapted to coöperate with projecting parts, situated in the frame, in such a manner that, when the sash approaches its 60 uppermost position, the yielding parts are pressed, by the said projections, toward the sash and are then allowed to expand, after having passed the said projections, so as to bear on the latter and assist in retaining the sash in its uppermost position, substantially 65 as and for the purpose set forth.

5. In a sash-window, the combination of spindles journaled in the frame, pulleys journaled about the said spindles, coiled springs attached, at their one ends, to the 75 spindles and, at their other ends, to the pulleys, means adapted to prevent the spindles from turning, springs situated in cavities in the spindles and acting to normally keep the said means operative, said means 80 being releasable by outward pressure, flexible connections between the pulleys and the sash, and elastically yielding parts carried by the sash, at the sides thereof, in operative relation to the pulleys so that, when the sash 85 approaches its uppermost position, the said yielding parts are pressed, by the pulleys, toward the sash and are then allowed to expand, after having passed the central parts of the pulleys so as to bear on the upper 90 halves of the said pulleys and assist in retaining the sash, substantially as and for the purpose set forth.

In testimony whereof I have signed my name to this specification in the presence of 95 two subscribing witnesses.

JOHN NERÉN.
